DESIGN FOR A REFRIGERATED DISPLAY CASE

George J. Hopkins, Kendallville, Ind., assignor to McCray Refrigerator Company, Kendall-ville, Ind., a corporation of Indiana

Application November 6, 1937, Serial No. 72,659

Term of patent 7 years

To all whom it may concern:

Be it known that I, George J. Hopkins, a citizen of the United States, residing at Kendallville, in the county of Noble and State of Indiana, have invented a new, original, and ornamental Design for a Refrigerated Display Case, of which the following is a specification, reference being had to the accompanying drawing, forming a part thereof, in which the figure is a front perspective view of refrigerated display case showing my new design, the distinguishing, essential and dominant features or characteristics of the design being the glazed doors of a different color than the predominating color of the case and the disposition of said doors at an angle, the rear of the case being plain and without doors.

I claim:

The ornamental design for a refrigerated display case, as shown and described.

GEORGE J. HOPKINS.
